UNITED STATES PATENT OFFICE

2,150,478

CONVERTIBLE CHAIR

Harry A. Yerrick, Toledo, Ohio, assignor to The
Hetzrick Manufacturing Company, Toledo,
Ohio, a corporation of Ohio

Application November 9, 1937, Serial No. 173,647

1 Claim. (Cl. 155—105)

This invention relates to articles of furniture but more particularly to chairs and an object is to produce a new and improved chair having the novel features of construction and arrangement enabling it readily and conveniently to be converted into a chaise longue.

Other objects reside in details of construction and arrangement and for purposes of illustration but not of limitation, an embodiment of the invention is shown on the accompanying drawing in which

Figure 1 is a rear perspective view of the chair; and

Figure 2 is a front perspective view of the chair converted into a chaise longue.

The illustrated embodiment of the invention comprises a chair having a frame composed of a pair of laterally spaced vertical legs 10 from the lower ends of which extend upwardly and rearwardly inclined rails 11, the legs 10 and rails 11 being integral with each other and joined by a rounded portion 12. The rear ends of the rails 11 are connected by a cross rod 13. Suitably mounted on opposite ends of the rod 13 are rubber tired wheels 14. Extending rearwardly from the upper ends of the legs 10 respectively and integral therewith are arm rests 15 the rear end portions of which are connected by a rod 16. Secured by bolts 17 to an intermediate portion of the legs 10 is a seat frame 18 of rectangular shape made up of rods suitably connected together and carrying a spring structure 19. At each corner at the front of the seat frame is a downwardly extending flange 20 which is engaged by the bolt 17. Hingedly connected to the rear end of the seat frame 18 is a back frame 21. The back frame 21 is also made up of rods and carries a spring structure 22. Secured to intermediate portions of the back frame 21 and at opposite sides thereof are plates 23 suitably notched to engage the transverse rod 16 to enable the back to be adjusted to one of several positions. This is accomplished by moving the back upwardly or downwardly to engage the rod into one notch or another.

Pivoted to the front end of the seat frame 18 is a foot rest 24 which is made up of a rod bent into U shape and having the ends thereof fitted into socket members 25 which pivotally engage the bolt 17. A cross rod 26 is disposed at the rear end of the frame 24. The frame 24 may be swung to the position shown in Figure 2 substantially in alignment with the seat frame and for holding the foot rest in this position, a U-shaped leg 27 is pivotally connected to the forward end portion thereof. For converting the chaise longue into a chair, the leg

27 is swung rearwardly and upwardly and then by lifting upwardly on the legs 10, sufficient room is afforded to allow the foot rest to be swung rearwardly and upwardly into the position shown in Figure 1. A hook 28 is connected to the lower cross rod of the back frame 21 and is engageable with the outer cross rod of the foot rest frame 24 for releasably holding the parts shown in Figure 1.

From the above description, it will be apparent that the chair can be readily converted into a chaise longue or from a chaise longue into a chair. The device can be readily moved from place to place on the wheels 14. The entire structure is exceedingly simple in construction and can be inexpensively manufactured in large scale production. Obviously, cushions are placed over the seat and back frame as well as the foot rest.

It is to be understood that numerous changes in details of construction, arrangement and operation may be effected without departing from the spirit of the invention especially as defined in the appended claim.

What I claim is:

25 A chair comprising a pair of spaced substantially C-shaped members, providing parallel base members, upright leg portions, and parallel arm-
rests, an axle connecting the rear ends of the base members, a transverse rod connecting the 30 rear ends of the arm-rests, a transverse pivot rod connecting the leg portions intermediate the ends of the latter, a seat frame connected at its forward edge to the transverse pivot rod, a substantially rectangular back frame pivotally connected to the seat frame, spaced slotted plates 35 carried by the back frame, each having one of the walls defining said slot notched to adjustably engage the transverse rod so as to support the back and seat frames in various positions of 40 adjustment, a substantially U-shaped leg rest having its free ends pivotally connected to the transverse pivot rod for movement to a horizontal operative position forwardly of the seat frame and for movement to a horizontal inoperative position substantially parallel with and beneath the seat frame, a U-shaped support having its free ends connected to the outer end of the leg rest for supporting the latter in its operative position, a pivoted strap carried by the 45 back rest, intermediate the sides of the latter and having a part formed to detachably engage the bight portion of the leg rest to support the latter in its inoperative position, and wheels carried by the axle for supporting the rear ends 50 of the base members above a supporting surface.

HARRY A. YERRICK.
